UNITED STATES PATENT OFFICE

WILLIAM WEBSTER WILSON, OF LOS ANGELES, CALIFORNIA

ROTARY WELL-BORING APPARATUS

Application filed October 5, 1926. Serial No. 139,590.

This invention has particularly to do with hydraulic rotary drilling apparatus, and more specifically with the rotary table of such apparatus. In rotary drilling rigs the rotary table is usually provided for the purpose of rotating the drill stem or pipe, rotary connection between the table and the drill pipe being effected usually by means of driving bushings. Such rotary tables usually have also some provision for taking pipe supporting slips. In some forms of these devices the pipe supporting slips are inserted and supported by the rotary table proper, or a part of the rotary table proper; and where that is the case it has been necessary to disconnect the two parts of the rotary table, hold the slip supporting part stationary, and rotate the remaining part of the table for the purpose of screwing or unscrewing pipe. In other types of rotary table structure there is an inner stationary part about which the table proper rotates; and this inner stationary part is constructed to receive supporting slips.

Ordinarily in the second mentioned type the inner stationary part comes up flush with the upper surface of the table proper; so that the slips will usually project above the upper surface of the table, and the drive bushing flanges also project above the upper surface of the table. These described relative arrangements and placements of the slips and drive bushings are also true of the first mentioned type. Among other objects and corresponding accomplishments which will hereinafter appear, it is an object of my invention to provide a construction wherein both the pipe supporting slips and the drive bushings may be set in operative position and not project above the upper surface of the table; and I prefer to incorporate these provisions in the second mentioned type of structure, although it will be understood that the same or similar provisions may be incorpo-

rated in the first mentioned type of structure.

For the purpose of describing in detail one concrete embodiment of the invention, I refer to the accompanying drawings, in which:

Fig. 1 is a plan of my improved rotary apparatus;

Fig. 2 is a section and elevation taken as indicated by line 2-2 on Fig. 1;

Fig. 3 is a plan of a drive bushing; and

Fig. 4 is a longitudinal central section of the same.

In the accompanying drawings and in the following specification, I do not attempt to go into detail regarding certain parts of the apparatus which are common in the art and are more or less universal to all devices of the character here described. For instance, the mounting of the apparatus on skids or sills, and the initial drive mechanism for the rotary table are things which are well known.

In the preferred form of device shown in the drawings a stationary base member B may be mounted on any suitable timbers T. This base member has a central up-standing hub 10, whose outer cylindric surface, as shown at 11, affords a cylindric bearing surface for the rotary table 12. Immediately surrounding the lower part of hub 10 and resting on the base flange 13 there is a bearing ring 14 on which the bearing rollers 15 run; and table 12 carries an upper bearing ring 16 running upon the rollers. Above bearing ring 16 the table has a cylindric bearing surface 17 which rotates against the cylindric bearing surface 11 of hub 10. The table is held down to its proper position on the bearings by a hold-down ring 18 which may be structurally tied to the base B in any suitable manner, as for instance by the brackets 19, one of which is shown at the right hand part of Fig. 2. Near its outer periphery and on its under face the table has gear teeth 20 which mesh with a driving pinion 21 mounted on drive shaft 22. One

bearing 23 for the drive shaft is indicated in the drawings; but the drive shaft may be mounted in any suitable or usual manner and may be driven through any suitable or usual drive. It has been usual in the past to place the hold-down ring in engagement with some lower part or flange of the rotating table; but I prefer to engage this ring with the upper outer edge of the table, so that the ring forms a stationary periphery for the whole device and the table is held down by application of force at its upper surface and at its outer periphery. Ring 18 may preferably be substantially L-shaped in section, with a part 18a bearing on the edge of the table and with the main part 18b engaging in an annular groove 18c, the outer edge of the groove being formed by a small annular rib 18d. The ring and table are thus held against any substantial relative radial displacement, although it will be understood that it is not the purpose to obtain any radial bearing between the ring and the table for the purpose of centering the table. Usually part 18b of the ring will fit loosely in the groove 18c as illustrated. The actual hold-down bearing surface is on the surface at the bottom of the groove 18c.

The upper surface S of the table stands considerably above the upper surface S1 of the base hub 10, substantially as shown in the drawings; and the table has a part 25 that overhangs the outer periphery of hub 10, as is clearly shown in the section at the left in Fig. 2. In the upper portion of the overhanging part bushing-engaging recesses 26 are formed, these recesses preferably having bottoms 27 within the table so that when the bushing is in place it will be supported by the table and not allowed to drop down to be supported by the stationary hub 10. Near its outer periphery and under the overhanging part 25 the bushing 10 has an annular drainage groove 28, and a depending annular flange 29 projects from the table into groove 28 as illustrated. One face of this annular flange, preferably its outer face, may be provided with a groove 30 which will retard overflow or splash of liquid to the outer bearing surface 11 of the hub. The purpose and function of groove 28 is to catch all liquid, such as water or mud or slush, which may fall upon the top of the bushing or the top of the table, and which would otherwise find its way to the bearings. For this purpose groove 28 is provided with drainage holes 31 which lead downwardly through hub 10 so that any such liquid is discharged to a point below the apparatus. It will be seen that the general arrangement I hereby describe, involving the relative placement of the table so that it may overhang the stationary base, facilitates very much the effective arrangement of the drainage groove 25 to effectually catch and carry off all the liquid

uids or other foreign material which might otherwise find its way to the rotary bearings.

To lubricate the bearing surfaces 11, 17 the surface 17 may preferably be provided with an annular oil groove 35 fed by channels 36 from a lubricant pocket 37 in the upper face of table 12. This lubricant pocket may well be an annular channel as shown in Fig. 1, although not necessarily so. In practice, channel 37 may be filled with some lubricant absorbing material which will deliver the lubricant slowly through channels 36 to the channel 35 and thus to the bearing surfaces 11, 17. The lubricant that flows down away from surface 17 then flows downwardly along surface 11 and finds its way to the bearing rollers 15. In flowing down surface 11 the lubricant will flow into a small annular pocket 40 which is formed between surface 11 and the lip 41 of bearing ring 14. Any dirt or grit thus has an opportunity to settle and the clear lubricant thus flows over lip 41 to lubricate the roller bearing. The roller bearing is protected from the outside by a depending flange 42 of the table which hangs down over the outer face of lower ring 14; and is also protected against entry of foreign substances by the interlocking formations 43 of the bearing rings 14 and 16. It is important in devices of the character herein described that all bearing surfaces shall be protected as fully as possible from mud, water, slush, etc., all of which are more or less continuously present about a derrick floor.

An outward extension 13a of base flange 13 forms an annular lubricant carrying pan surrounding the roller bearing and into which pinion 21 dips for its lubrication. The spent lubricant may finally overflow the upper edge of 13a.

The upper face of table 12 is provided with the usual sockets 45 to receive the posts for driving tongs or the like (these posts are usually known as "go-around" posts) and stationary hub 10 is likewise provided with a socket or sockets 46 to receive stationary posts, usually known as "hold-back" posts, for engaging and holding tongs or similar apparatus. It is unnecessary to describe how these sockets and their corresponding posts are used for the purpose of setting up or breaking joints, as that will be well understood. It will be seen that my arrangement provides a very ready and convenient mounting at these posts and provides for the immediate use of either one or both of them without any necessity of making any adjustments or changes in the table mechanism.

The central base hub 10 has a central downwardly tapering opening 50 adapted to receive wedge slips of any usual kind, the position of the slips being indicated by the dotted lines at 51 in Fig. 2. These slips are usually made of such size with relation to the size of opening 50 and the size of the pipe that their

upper ends, or handles which are usually applied to their upper ends, will project above the upper surface S—1 of the stationary hub; but in my construction the upper surface S of table 12 is sufficiently above surface S—1 that the uppermost parts of the slips will be below surface S. Consequently the combined use of the slips and pipe elevators is greatly facilitated as an elevator may rest upon the upper surface of the table without interfering with the slips. In the ordinary construction, where the slips project above the upper surface of the table, they must be removed before an elevator can be rested on the table.

15 Likewise the drive bushings are made to rest entirely below, or substantially entirely below the table surface S. In Figs. 3 and 4 I show a form of drive bushing suitable for the purposes. Drive bushings used in rotary 20 outfits usually have a sleeve portion 52 with an interior opening 53 of a form to engage the "Kelly" (the length of drill stem or pipe through which rotary motion is imparted to the string) and these bushings usually have an 25 upper flange or flanges 54 and are usually split in some manner or other, as by the split shown at 56. However, bushings of this general nature are usually so constructed that the flange 54 rests over the top of the rotary table, being driven by engagement with a pin or post. 30 In my preferred construction I provide the before mentioned recesses 26 in the inner periphery of the table and I provide the drive bushing flanges 54 with corresponding lugs 35 55 to engage in those recesses. When the drive bushing is in position, as shown in dotted lines in Fig. 2, its upper surface is preferably either flush with or below table 40 surface S, and the drive bushing is supported by the engagement of lugs 55 with bottoms 27 of recesses 26; so that there is no projection of the bushings above the top of the table and also the bushings do not at any place rest upon the stationary base or its central 45 stationary hub 10. Preferably the sleeve portions 52 of the bushings will be of such size that although they extend down through hub opening 50, they do not at any place bear upon the hub.

50 The lower end of the central opening in the hub may be flared downwardly as shown at 50a to guide a drill stem or pipe collar into the central opening without catching on the lower end of the hub.

55 I claim:

1. Rotary drilling apparatus of the character described, comprising a stationary base with a central hub having a vertical, central pipe-passing opening therethrough, a rotary 60 table surrounding said hub with radial bearings thereon and supported on bearings on the base with its upper surface at an elevation above the upper surface of the hub, said table having a central opening, and a hold-down 65 ring surrounding and bearing upon the upper

part of the table adjacent its outer periphery and connected with the stationary base.

2. Rotary drilling apparatus of the character described, comprising a stationary base with a central hub having a vertical central pipe-passing opening therethrough, a rotary 70 table surrounding said hub with radial bearings thereon and supported on bearings on the base with its upper surface at an elevation above the upper surface of the hub, said table 75 having a central opening, the table having in its upper surface and adjacent its outer periphery an annular groove, and a hold-down ring with an annular part entering said groove and bearing upon its bottom and with a part overhanging the outer edge of the table, said hold down ring being rigidly connected with said base.

3. Rotary drilling apparatus of the character described, comprising a stationary base 85 with a central hub having a vertical central pipe-passing opening therethrough, a rotary table surrounding said hub with radial and vertical bearings on the hub and base, said 90 table having a central opening, the table having in its upper surface and adjacent its outer periphery an annular groove, and a hold-down ring with an annular part entering said groove and bearing upon its bottom with a part overhanging the outer edge of the table, said hold down ring being rigidly connected with said base.

4. Rotary drilling apparatus of the character described comprising a stationary base with a central hub having a vertical, central pipe-passing opening therethrough, a rotary 100 table surrounding said hub with a radial bearing thereon, means for lubricating said radial bearing, a vertical thrust bearing for the table upon said base and surrounding the lower part of said hub below the radial bearing, said radial and thrust bearings being so 105 relatively arranged that lubricant from the radial bearing gravitates to the thrust bearing, an outward annular extension of the base forming a lubricant pan outside said thrust bearing and into which lubricant is adapted to gravitate from the thrust bearing, said 110 pan and the lubricant level therein being below the level at which the lubricant flows from said thrust bearing, and means to drive the rotary table including a drive pinion dipping into said lubricant pan.

5. Rotary drilling apparatus of the character described comprising a stationary base 120 with a central hub having a vertical, central pipe-passing opening therethrough, a rotary table surrounding said hub with a radial bearing thereon, means for lubricating said radial bearing, a vertical thrust bearing for the table upon said base and surrounding the lower part of said hub below the radial bearing, said radial and thrust bearings being so 125 relatively arranged that lubricant from the radial bearing gravitates to the thrust bearing.

ing, an outward annular extension of the base forming a lubricant pan outside said thrust bearing and into which lubricant is adapted to gravitate from the thrust bearing, said pan and the lubricant level therein being below the level at which the lubricant flows from said thrust bearing, means to drive the rotary table including a drive pinion dipping into said lubricant pan, and means for providing a tortuous path for the lubricant between said thrust bearing and the pan.

In witness that I claim the foregoing I have hereunto subscribed my name this 6th day of September, 1926.
